UNITED STATES PATENT OFFICE.

FRANCIS M. BAKER, OF ST. LOUIS, MISSOURI, ASSIGNOR OF ONE-HALF TO
JAMES T. SANDS, OF SAME PLACE.

SASH-BALANCE.

SPECIFICATION forming part of Letters Patent No. 427,389, dated May 6, 1890.

Application filed February 20, 1890. Serial No. 341,159. (No model.)

To all whom it may concern:

Be it known that I, FRANCIS M. BAKER, of St. Louis, in the State of Missouri, have invented certain new and useful Improvements 5 in Sash-Balancing Devices, of which the following is a full, clear, and exact description, reference being had to the accompanying drawings, forming a part hereof.

My invention relates to that class of devices 10 in which the window-sashes are balanced by weighted racks and pinions; and it consists in the novel construction, combination, and arrangement of parts hereinafter set forth, and particularly pointed out in the claims.

15 In the drawings, Figure 1 is a perspective view of a sash and improved weight. Fig. 2 is a sectional elevation of the sash and weight, the weight being located in its removable shell or box. Fig. 3 is a side elevation 20 of a weight detached. Fig. 4 is a face view of same. Fig. 5 is a perspective view showing the front of one of the removable weight shells or boxes. Fig. 6 is a like view showing the back of same; and Fig. 7 is a sec-

25 tional plan view showing the weight-box located in the ordinary window-frame, the section through the said box being taken on line xx , Fig. 5.

1 represents the ordinary sashes, having 30 the racks 2 set in grooves 3 in the edges of said sashes, by means of which the retaining-strips, such as 4, which are provided in all ordinary windows, may be used full size, as it is obvious that said racks 2 are thereby set 35 entirely within the sash and do not project to interfere with the strips 4, which are applied to the window-frame 5 in the ordinary manner. (See Fig. 7.)

6 is the weight, any number of which may 40 be used, and which has rack 7 cast integral with its front side, and a roller 8, journaled between inwardly-projecting lugs a , also cast upon its lower end, so as to be projected inwardly a sufficient distance to have a bearing 45 against the inner surface of the stile-board b , and so prevent tipping of the weight during upward movement of same, which I have found by experiment would occur were said roller not so provided. 9 is an upper

roller located at the upper end of said weight 50 and journaled between ears c , which are cast upon the weight so as to project inwardly a sufficient distance to bear against the stile-board b , and thereby guide the upper end of the weight and prevent its inward tipping 55 and consequent pressure against the pinion 17, said upper roller being located at one side of the weight-rack 7, so as not to interfere with the length of same. The weights are cast in the form of a hollow shell, with a passage-way 10 extending through their bodies, beginning at their upper ends, whereby slugs or small pieces of weighty material—such as lead or iron—may be inserted, for the purpose of altering the gravitation of the weights 60 without altering their external contour, as will be readily understood.

d indicates the slugs of lead or other material located in the hollow weights. To prevent backward tipping of the weights, I may likewise apply rollers 11 (indicated by dotted lines in Fig. 3) to the back of them, at either top and bottom or at top only.

12 indicates the removable and adjustable box in which the weights and pinions are located. It preferably consists of a rectangular box having one end and side open, the same being the side next adjacent to the sash, and having three vertical plates 13, which are provided at the proper height with holes or 75 bearings 15 for the spindle 16, which extends across the box and carries pinions 17 thereon in position to mesh with the racks on the weights. It will thus be seen that slideways are formed in said removable boxes, in which 80 the weights move up and down and are guided in a perfectly-vertical line without imposing 85 undue pressure or friction on the pinions.

At the back of each box and in the closed rear side of each slideway f horizontal openings 19 are cut, and rollers 18 are properly journaled therein, against which the weights slide during operation. Instead, however, of making use of these last-named rollers I may 90 discard them and bring into use the construction shown in Fig. 3 in dotted lines, in which 95 are shown rollers journaled upon the back of the weight, the construction in either case per-

forming the same function—viz., guiding the back of the weights and obviating any tendency to backward tipping of same, which has heretofore occurred in mechanisms of this 5 character, causing the same to run very hard.

The operation is as follows: Should it be desirable to apply my improvement to a window already constructed, and, say, provided already with weights and cords of ordinary 10 form, I first remove a portion of the inner casing (or it may be all) h , which will permit of sliding the box 12 directly into place, when all that will further be necessary will be to cut grooves in the sashes and apply the 15 sash-racks thereto, all as before set forth.

By such construction the invention may readily be applied to windows of ordinary construction without a great amount of alteration being done to them, the removable box 20 being complete within itself, carrying the weights for both upper and lower sashes, with their pinions and rollers necessary to insure successful operation for a comparatively unlimited length of time.

25 The improved weights, being hollow, can be made heavier or lighter to suit different weights of sash, in the manner before described.

The removable box can be made either of

cast metal, which I prefer, or it may be built 30 up of wood.

I make no claim to the devices shown in United States Patents Nos. 7,003 and 321,035; but

What I claim is—

1. A balancing-weight having a toothed rack 7 cast integral with its front face and a roller or rollers journaled to project from said front face, substantially as herein set forth. 35

2. A balancing-weight having a toothed rack 7 and lugs a cast integral with the body thereof, so as to project inwardly from said body, and roller-carrying lugs projecting from the back in a plane with said inwardly-projecting lugs, for the purpose substantially as 40 45 set forth.

3. As an improved article of manufacture, a hollow sash-weight having rack-teeth cast integral with its inner face, the said inner face also having lugs or projections in which 50 are secured rollers, substantially as described.

In testimony whereof I affix my signature in presence of two witnesses.

FRANCIS M. BAKER.
